UNITED STATES PATENT OFFICE

159,993

SCHOOL DESK

Ernest J. Kump, Jr., San Francisco, Calif.

Application May 2, 1949, Serial No. 2,373

Term of patent 14 years

(Cl. D33—11)

To all whom it may concern:

Be it known that I, Ernest J. Kump, Jr., a citizen of the United States, residing at San Francisco, in the county of San Francisco and State of California, have invented a new, original, and ornamental Design for School Desk, of which the following is a specification, reference being had to the accompanying drawing, forming part thereof.

Fig. 1 is a perspective view of a school desk, showing my new design.

Fig. 2 is a side view of the school desk.

Fig. 3 is a rear view of the school desk.

I claim:

The ornamental design for a school desk, as shown.

ERNEST J. KUMP, JR.
